UNITED STATES PATENT OFFICE

PETER R. ALPHONSO, OF LONGVIEW, TEXAS, ASSIGNOR TO THE ARGENT CORPORATION,
OF SHREVEPORT, LOUISIANA, A CORPORATION OF LOUISIANA

LIQUID LIFT PUMP

Application filed March 26, 1932. Serial No. 601,392.

The invention relates to fluid lift pumps used in connection with artesian wells, and has for its object to provide a device of this character comprising a casing 5 into the lower end of which fluid in the well rises, under natural pressure; an axially and centrally disposed discharge pipe within the casing and means whereby air or other pressure may be forced downwardly between the 10 discharge pipe and casing wall for exerting pressure on the liquid in the casing and forcing the liquid upwardly through the axially and centrally disposed discharge pipe, thereby reducing the area of liquid contact surface 15 to a minimum.

A further object is to provide a fluid lift pump comprising a discharge pipe within and in spaced relation to the inner periphery of a well casing, and through which discharge 20 pipe liquid is forced upwardly by pressure, forced downwardly through the casing around the discharge pipe. The discharging through the discharge pipe, instead of between the discharge pipe and casing, reduces 25 the friction on the liquid to a minimum.

A further object is to interpose in the discharge pipe line a connecting member substantially Y-shaped, to the lower arm of which is connected a depending portion of the discharge 30 pipe in a manner whereby air, passing downwardly through the Y and around the upper portion of the discharge pipe, will be discharged into the lower end of the casing for forcing liquid upwardly and between the 35 arms of the Y-shaped member into the discharge pipe connected to the Y-shaped member.

A further object is to provide a detachable connection between the upper portion of the 40 discharge pipe and the upper end of the Y-shaped member for supporting the upper portion of the discharge pipe, and to provide a threaded connection between the upper portion of the casing and the upper portion of 45 the Y-shaped member within the upper end of the lower large portion of the casing, and to provide a packing joint for preventing leakage.

A further object is to provide one of the 50 casing sections with a sleeve, in which is

threaded a bushing, which in turn has threaded therein a packing connection sleeve and lock nuts threaded on said sleeve and cooperating with the bushing for holding the same in adjusted position. 55

A further object is to provide a slide piston in the lower end of the casing and controlling an intake port through which liquid, such for instance as oil, rises into the lower end of the casing, after passing through apertures 60 in an inner casing and means whereby air forced downwardly through the chamber around the discharge pipe will lift said liquid to the discharge pipe.

A further object is to provide a fluid pump 65 comprising an inner and outer casing, and means whereby air pressure may be forced downwardly between the casings to a point adjacent the lower ends thereof and then bypassed into the inner casing and discharged 70 between the casings in a position where liquid will be lifted thereby, and which liquid is finally discharged from the pump through the inner casing. 75

A further object is to provide a fluid pump 80 with means whereby fluid naturally arising in the pump will be forced from the pump or well by air pressure transferred from casings within each other to positions where fluid will be first lifted between casing sections and finally discharged through the inner casing, thereby reducing the frictional engagement of the fluid with contacting surfaces to a minimum. 85

A further object is to provide a sliding valve in the lower end of the inner casing, which valve is normally maintained in raised position, allowing flow of fluid under natural pressure into and between the casings, 90 and which valve, upon initial air pressure, is seated thereby by-passing the air pressure between the casings for lifting the fluid.

With the above and other objects in view the invention resides in the combination and arrangement of parts as hereinafter set forth, shown in the drawings, described and claimed, it being understood that changes in the precise embodiment of the invention may be made within the scope of what is 100

claimed without departing from the spirit of the invention.

In the drawings:

Figure 1 is a vertical transverse sectional view through the upper portion of the device.

Figure 1a is a vertical transverse view through the lower portion of the device.

Figure 2 is a vertical longitudinal sectional view through the central portion of the device, taken at a right angle to that shown in Figure 1.

Figure 3 is a horizontal sectional view taken on line 3-3 of Figure 2.

Figure 4 is a horizontal sectional view taken on line 4-4 of Figure 1a.

Figure 5 is a horizontal sectional view taken on line 5-5 of Figure 1a.

Referring to the drawings, the numeral 1 designates the upper section of the well casing and 2 the lower section, which sections are adapted to be disposed in a well in the usual manner. The upper section 1 of the casing is of smaller diameter than the lower section and extends downwardly into the upper end of the lower section 2 as clearly shown in Figure 1. Threaded at 3 on the upper end of section 2 of the casing is a sleeve 4, in which sleeve is threaded a bushing 5, which supports the packing sleeve 6, which is threaded at 7 therethrough. It will be seen that by adjusting the bushing 5, packing sleeve 6 may be adjusted upwardly or downwardly to accommodate the same to the packing gland 8. Threaded on the packing sleeve 6 is a lock nut 9 for locking the sleeve against rotation after an adjustment thereof. Slidably mounted on the casing section 1, and extending into the sleeve 6 is a gland bushing 10 which cooperated with the packing 8 for forming a water or fluid tight connection. Packing material 8 may be of any kind, for instance, lead or a fibrous material.

Extending axially downwardly into the upper casing section 1 in spaced relation thereto is a discharge pipe 10a through which liquid is forced upwardly by air forced downwardly in any suitable manner through the chamber 11, around the discharge pipe 10a. It will be noted, by forcing the air through the chamber 11 and lifting the fluid through the pipe 10a, the frictional engaging surface of the fluid is reduced to a minimum, thereby reducing the amount of power necessary for the fluid lifting operation.

Threaded at 12 on the lower end of the upper casing section 1 is a yoke 13, having an annular passage therein designated by the numeral 14, and through which passage air from the annular air chamber 11, around the discharge pipe 10a, passes to the U-shaped air passage 15 in the U-shaped supporting member 16, which supporting member supports the air supply pipe 17, which extends downwardly centrally and axially into the

lower casing section 2. It will be noted that the air, when passing through the upper casing section 1, is outside the discharge pipe 10a, but when it passes downwardly into the lower casing section 2, it is centrally of said lower section and is discharged into the chamber 18 through apertures 19 for lifting liquid which has previously risen into the casing chamber 18, around air pipe 17. Threaded on the lower end of the discharge pipe 10a is a sleeve 20, and connecting said sleeve and the member 13 is a nipple 21, through which liquid forced upwardly in the direction of the arrows a, pass, and it will be noted by providing a U-shaped member 16, the liquid will pass between the arms 16a thereof, so that it may be discharged axially upwardly through the discharge pipe 10a for reducing the frictional engagement of the liquid with pipe surfaces to a minimum.

Air pipe 17 has its lower end provided with an enlargement 22 on which is threaded the bell 23 of a perforated cylinder 24, and through which cylinder the perforations 19 extend. Disposed within the bell 23 of the cylinder 24 is a disc 25 having apertures 26 therethrough, allowing passage of air, and also forming a guide for a valve stem 27. A spring 27a is provided which maintains the valve stem 27 normally in dotted line position as shown in Figure 1a until air pressure is forced through the device.

Threaded on the lower end of the casing section 2 is a base member 28, in which is threaded the nipple 29, which is, in turn, threaded at 30 on the lower end of the cylinder 24, and is provided with a valve seat 31, with which the valve 32 cooperates. In the present device there is absolutely no pumping operation, and one of the main functions of the valve is to obviate any possibility of a suction in the bottom of the casing, which would stir up sand or agitate the material being lifted.

Referring to Figure 1a, the piston 32 is shown in its lower position seated on the valve seat 31 for cutting off the flow of fluid into the casing under natural pressure. The air forcing operation, hereinafter set forth, is an intermittent one, and may vary as desired. With the showing in Figure 1a, air pressure is in the device, having been forced downwardly between the upper casing section 1 and the inner discharge pipe 10a, thence through the U-shaped passage 15, through the pipe 17, disc 25, pipe section 24, where it has forced the piston 32 downwardly from the dotted line position to the full line position. Previously, fluid under natural pressure has risen in the device, particularly in the pipe 24 and has passed through the apertures 19, assuming the liquid level 2a shown in Figures 1 and 2.

After the downward movement of the piston 32 for sealing the device against further

inflow of fluid from the well, the air pressure passes through the apertures 19 and forces the liquid in the chamber 18 upwardly, and transfers the same in the direction of the arrows *a*, Figure 1, into the centrally disposed discharge pipe 10*a*. It will be noted that by discharging the fluid through a centrally disposed pipe 10*a*, that the frictional engagement of the fluid or liquid with the walls of the casing is reduced to a minimum, thereby allowing the use of a minimum amount of air pressure. This is an essential point when it is considered that wells of this character are several thousand feet deep. It is obvious that if the liquid were discharged between the inner and outer casing 1 and 10*a*, there would be a maximum contact surface which would require a far greater air pressure. After the first lifting operation, air pressure is cut off and the expansive action of the spring 27*a* will raise the piston 32 to the dotted line position shown in Figure 1*a*, thereby uncovering the apertures 19 and again allowing the casing section chamber 18 to again fill under the natural pressure of fluid from the well. A double piston is shown which cooperates with the apertures 19 whereby when the piston is in raised position, there will be a rapid filling of the chamber 18, and when in lowered position will uncover sufficient apertures for air pressure purposes. It is to be understood that any means may be used for supplying the air pressure, and the discharge pipe 17 may lead to any suitable source of discharge.

From the above it will be seen that a well pumping device is provided which is simple in construction, one wherein air is used for forcing liquid from the well, and simultaneously sealing the bottom of the well against sand and foreign matter, thereby allowing operation of the device at great depth. It will also be seen that the range of operation is materially increased by discharging the liquid from the centrally disposed discharge pipe where frictional surfaces are reduced to a minimum and utilizing the annular chamber around the discharge pipe for the air pressure. It is to be understood that steam may be used instead of air for lifting purposes, if desired.

The invention having been set forth what is claimed as new and useful is:—

55 1. A well pump comprising a casing adapted to be disposed in a well, a valve carried by the lower end of said casing and moved to open position upon relief of fluid pressure within the well, a liquid discharge pipe disposed within the casing in spaced relation thereto thereby forming a chamber around the discharge pipe through which air may be forced downwardly, means whereby air forced downwardly through the casing around the discharge pipe will engage

and seat the valve and will lift liquid within the casing and force the same upwardly through the discharge pipe.

2. A well pumping and discharging device comprising a casing adapted to be disposed in a well, into which liquid naturally rises, means for admitting liquid to the lower end of the casing as it rises in the well, a normally open valve controlling the flow of liquid into the casing, said valve being slidably mounted in a perforated pipe section in the lower end of the casing and through the perforations of which liquid passes to a chamber around the perforated pipe section, a liquid discharge pipe extending downwardly into the casing in spaced relation thereto, thereby forming an air passage around the discharge pipe and means whereby air passing through said air passage will be discharged into the perforated pipe section and seat the valve, the continued lifting of the liquid maintaining the valve seated, said liquid being discharged through the discharge pipe.

3. A well pumping and discharging device comprising a casing adapted to extend downwardly into a well, said casing comprising an upper casing section, a lower casing section of greater diameter than the upper casing section, a coupling connection between the upper and lower casing section, a discharge pipe extending downwardly into the upper casing section and terminating adjacent its lower end, and forming an annular chamber through which air may be forced, a Y-fitting connected to the lower end of the upper section and through which air is forced.

4. A well pumping and discharging device comprising a main casing, means for admitting fluid into the lower end of the main casing, a liquid discharge pipe centrally of the casing, an air discharge pipe extending to the bottom of the casing in alignment with the liquid discharge pipe, a Y-connection between a portion of the main casing and the air discharge pipe whereby air, passing downwardly around the discharge pipe, will enter the air discharge pipe for raising the liquid into the lower end of the casing and discharging the same upwardly through the discharge pipe.

5. A well pumping and discharging device comprising a casing, a liquid discharge pipe extending downwardly into said casing and forming an air passage around the discharge pipe, a Y-connection between a portion of the casing, the discharge pipe and the air supply pipe extending downwardly in the casing, said Y forming means, whereby liquid forced upwardly in the casing will pass through the discharge pipe.

6. A well pumping and discharging device comprising a casing, said casing comprising an upper section, a lower section, a pack joint

connection between said sections, a discharge pipe extending axially through the upper section in spaced relation thereto, thereby forming an air passage, a Y connection carried by the lower ends of the upper casing section and the discharge pipe and having air passages therethrough, an air discharge pipe connected to said Y and extending downwardly into the lower casing, a valve in the 10 lower end of the casing, means for normally maintaining said valve open, said valve being closed by downwardly discharged air pressure, said air pressure forming means whereby liquid is forced upwardly around 15 the Y and through the discharge pipe.

7. A well pumping and discharging device comprising a casing having upper and lower sections, a packed coupling connection between said sections, the upper section being 20 smaller than the lower section, a liquid discharge pipe extending downwardly into the upper section in spaced relation thereto, thereby forming an air passage around the discharge pipe, a Y-coupling carried by the 25 lower end of the upper casing section, the arms of said Y coupling being disposed at opposite sides of the discharge pipe thereby forming passages of communication with the chamber of the lower section of the casing 30 and an air discharge pipe connected to the Y-coupling and extending downwardly into the lower casing.

8. A well pumping and discharging device comprising a casing having upper and lower 35 casing sections, coupling sections between said sections, a liquid discharge pipe extending downwardly through the upper section in spaced relation thereto, thereby forming an air passage around the discharge pipe,

40 a chambered member threaded on the lower end of the upper casing section, a coupling connection between said member and the discharge pipe, a U-shaped connection carried by said chambered member and having

45 its arms connected to the chambered member at opposite sides of the coupling connection with the discharge pipe and provided with chambers in communication with the chamber of the chambered member and a down- 50 wardly extending air discharge pipe carried by the U-shaped connection and terminating adjacent the lower end of the lower casing section.

9. An oil well comprising inner and outer 55 casings, a normally open valve carried by the lower end of the inner casing and above intake ports in communication with the outer casing and means whereby air forced downwardly through the outer casing around the inner casing will be by-passed into the lower 60 end of the inner casing and seat the valve below the ports of communication between the inner and outer casings and the continued air pressure will pass through said ports, lift 65 the fluid in the lower end of the outer casing

and means whereby said fluid is by-passed into the inner casing above the valve.

10. The combination with a fluid lifting well pump comprising inner and outer casings, valve means in the lower end of the inner casing and normally above ports of communication between the inner and outer casing, thereby allowing fluid under natural pressure to rise in the outer casing, of means whereby air forced through the outer casing around the inner casing will be by-passed into the inner casing against the valve for seating the valve below the ports of communication between the casings and the continued forcing of air will lift the fluid in the outer casing and by-pass the same into the inner casing above the valve. 70 75 80

11. The combination with a fluid well lifting device comprising inner and outer casings, ports of communication between said casings adjacent their lower ends, a valve within one of said casings and normally disposed above ports of communication between the casings, spring means for normally maintaining said valve in raised position, of means whereby fluid accumulated in the lower ends of the casings will be forced upwardly through the outer casing and by-passed into the inner casing above the valve by air forced downwardly through the outer casing around the inner casing and by-passed into the inner casing above the valve. 85 90 95

12. The combination with a fluid pressure well comprising inner and outer casings, into the lower end of which fluid under natural pressure rises, of means whereby when air is forced downwardly through the outer casing around the inner casing, fluid from the well will be cut off and the air diverted whereby liquid will be forced upwardly and bypassed into the inner casing. 100 105

13. The combination with a fluid pressure well comprising inner and outer casings, a normally raised spring actuated valve in the lower end of the said inner casing above ports of communication between the casing chambers and into which liquid under natural pressure rises, of means whereby air forced downwardly through the outer casing around the inner casing will be by-passed into the inner casing above the valve means for forcing the same to closed position and means whereby said air pressure will be diverted through the ports of communication with the outer casing chamber whereby liquid therein will be lifted and by-pass means between the chamber of the outer casing and the inner casing above the valve, and through which means the liquid is forced. 110 115 120

14. The combination with a pressure well comprising inner and outer casings into the lower ends of which fluid under natural pressure rises, an air controlled valve in the lower end of the lower casing for controlling the flow of liquid into the casing, of means where- 125 130

by air forced downwardly through the main casing will be by-passed into the lower end of the inner casing for moving said valve to closed position, means for by-passing said air 5 into the outer casing for lifting liquid in the outer casing and means whereby said liquid is by-passed into the inner casing.

In testimony whereof he hereunto affixes his signature.
